**COMBINED CLEANING ELEMENT HOLDER AND
HANDLE SOCKET OR SIMILAR ARTICLE**

Richard S. Cowen, 33 Glen Eagles Drive,
Larchmont, N.Y.

Filed Aug. 10, 1964, Ser. No. 81,232

Term of patent 14 years

(Cl. D9—2)

FIG. 1 is a front elevational view of a combined cleaning element holder and handle socket or similar article showing my new design.

FIG. 2 is a rear elevational view of the same.

FIG. 3 is a plan view of the same.

FIG. 4 is a side elevational view thereof.

The dominant features of my design reside in the portions shown in solid lines.

I claim:

The ornamental design for a combined cleaning element holder and handle socket or similar article, as shown and described.
